METHOD OF MAKING ICE IN SMALL PIECES

Francis M. Raver, York, Pa., assignor to Flakice Corporation, Brooklyn, N. Y., a corporation of Delaware

Application November 18, 1942, Serial No. 465,955

2 Claims. (Cl. 62—105)

1

This invention relates to method and apparatus for continuously removing brittle substance from a rigid freezing surface on which said substance is continuously congealed from a fluid state. More particularly, the invention relates to the manufacture of ice pieces for refrigeration purposes, said pieces having extensive width and length dimensions, and small thickness dimensions, whereby said ice pieces present maximum surface area per unit of mass and maintain substantially constant surface area during 90% of the melting of the ice pieces.

An object of the present invention is to provide improved method and apparatus for manufacturing ice pieces by freezing water on a rigid cylindrical surface and removing ice therefrom in the form of pieces as above described.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the drawings:

Figure 1 is a perspective view of apparatus embodying the invention;

Figure 2 is a reduced vertical axial cross-section of the cylinder of Figure 1; and

Figure 3 is a diagrammatic perspective view of a portion of an ice layer being freed from the surface on which it is frozen.

Referring to Figure 1, a tank or compartment 10 is shown for holding water to be frozen. Rotatably supported in the tank so as to be more than 50% submerged is a freezing cylinder, generally indicated at 11, having a cylindrical freezing surface 12.

Referring to Figure 2, the cylinder is suitably mounted on a shaft 15 supported in bearing assemblies 13 and 14, the right hand one 13 of which is broken away to show its general construction. This assembly is identical to that shown in my U. S. Patent 2,344,922, issued March 21, 1944, and is adapted to permit passage of refrigerant to and from the cylinder. The left hand bearing 14 is of the usual construction to prevent flow of water from the tank along the shaft 15.

2

The shaft 15 is provided with an outer concentric passage 18 for conducting liquid refrigerant from a compressor and condenser system, diagrammatically indicated at 16, into the evaporating space of the cylinder. The liquid refrigerant is conducted to the concentric passage through a pipe 17. The shaft assembly is provided with an inner concentric passage 19 to conduct spent refrigerant from the cylinder to a pipe 20 which takes the spent refrigerant back to the system 16.

The cylinder is continuously rotated by means of a gear 21, secured to the shaft 15, and driven through a suitable pinion 22, driven by an electric motor 23, provided with a suitable change speed reducing gear.

The temperature inside the cylinder is maintained at whatever temperature is desired in any suitable manner, or by the usual differential valve 20 controlling the flow of liquid refrigerant to the evaporator in response to the temperature of the spent refrigerant and to the pressure of the spent refrigerant.

The water in the tank is maintained at the desired level by any suitable means, such as a float valve (not shown). The makeup water controlled by the float valve is supplied through a pipe 24 emptying directly into tank 10.

As the cylinder 11 rotates, an ice sheet builds 30 up on the submerged portion of the surface 12, and as the ice sheet moves out of the water it passes under a cutting unit, generally indicated at 29, which in appearance resembles a lawn mower cutter. As the ice sheet passes under the 35 cutting unit, successive leading portions of the ice sheet are severed from the ice sheet and are freed from the surface 12 in the form of ice pieces having relatively large length and width dimensions and relatively small thickness dimensions 40 as above described.

The thickness of the ice sheet and of the resulting pieces depends on the speed of rotation of the cylinder, providing the rate of refrigeration of the cylinder is kept constant. If the speed 45 is increased, the thickness is reduced and vice versa. The speed may be set by the reducing gear unit provided with the driving motor.

The cutting unit has a plurality of helically shaped blades, and is mounted on a shaft 31 50 which rotates in bearings 30. The axis of shaft

31 is directly above and parallel to the axis of the cylinder 11. The shaft 31 is so adjusted with respect to the cylinder 11 that the sharp beveled edges of the helical blades very nearly contact, but do not touch the surface 12, as the cutting unit and cylinder rotate.

On the shaft 31 supporting the cutting unit is secured a pinion gear 32, driven by another pinion 33, which in turn is driven by a motor 34 provided with a suitable change speed reduction unit so that the surface (peripheral) speed of the cutting unit and the surface speed of the cylinder 11 may be adjusted relatively to each other. The drive is such that as each blade approaches the surface 12, the blade is travelling in the same direction as the surface 12.

As the cylinder turns, the ice pieces that are freed by the cutting unit are taken off of the cylinder by a doctor 35, located above the water level in the tank 10.

Referring to Figure 3, the operation of the ice cutting unit is diagrammatically illustrated. The ice sheet A formed on the cylinder surface 12 has a thickness B. The blade 29a has just severed an ice portion C from the ice sheet A and has freed the ice portion from the surface 12. The ice portion is broken up into pieces D during the operation, which pieces will subsequently slide off on the doctor 35.

The problem of removing ice from a rigid surface on which it is frozen has long been recognized as a difficult one. Scraping ice from such a rigid surface is an unsatisfactory method in that it produces only small particles of ice, commonly called mush ice, and such ice can be handled practically only by mixing it with water or compressing it into briquettes.

In an application having Serial No. 187,761, filed January 29, 1938, (now issued as U. S. Patent No. 2,310,468) Frank Short disclosed a novel method and apparatus for removing ice in the form of pieces, such as above described, from a rigid surface on which the ice is frozen, by exerting on an ice sheet formed on a rigid cylinder surface a force acting along a line spaced inwardly from but parallel to the leading edge of the ice sheet. The force has a component action to sever the portions thus segregated from the ice sheet, and a component action through the body of the ice portion to overcome the bond of adhesion between the ice portion and the surface, without overcoming the compressive strength of the ice portion; i. e., without breaking it into ice particles. In the Short apparatus the force was applied by a blade moving radially into the ice sheet while having no circumferential component of motion with respect to the ice sheet.

I have discovered that by applying the force through the medium of a blade that has a peripheral speed greater than that of the ice sheet on the cylinder, improved results can be obtained in the freeing of the ice pieces from the cylinder, in that a thinner ice sheet may be operated on by the cutting unit to satisfactorily remove the ice in the desired form of ice pieces. This makes the apparatus more economical because within limits the thinner the ice sheet the greater is the production capacity of the apparatus. This follows because as the ice sheet increases in thickness, it offers very much greater resistance to heat flow through it and the freezing rate of the ice is reduced. Also thin ice pieces are desirable because their melting rate remains more constant than that of thicker ice pieces.

To this end, in the present embodiment the blades of the ice cutting unit are positively driven and at a rate to give the blades a surface or peripheral speed greater than that of the cylinder. As the ratio of the peripheral speed of the cutter to the peripheral speed of the cylinder is increased from a ratio of 1:1, the ice removal of the ice cylinder improves until the ratio becomes so high that the cutting unit acts as a shaving apparatus instead of an ice piece removing apparatus.

In one specific embodiment of the invention in which the cutting edges of the blades were beveled, as shown in Figure 1, and in which the blade edges had a radius of $1\frac{25}{32}$ inches (with reference to the axis about which the blade edges turn), and in which the surface of the cylinder had a radius of 9 inches, the ice sheet approximately one eighth inch thick was not removed or freed by the cutting unit and was not removed by the doctor 35 until a ratio of peripheral speed of the blade to peripheral speed of the surface 12, of 3:1 was reached; i. e., in which the peripheral speed of the blades was three times faster than that of the cylinder. But at this ratio and up to a ratio of 5:1, although the ice was not entirely freed by the cutter, it was sufficiently loosened so that the collecting blade or doctor 35 removed it from the surface 12. This operation was obtained with a circumferential spacing between the edges of the blades of $1\frac{25}{64}$ inches. This same satisfactory operation was obtained with a circumferential spacing of the blades of $4\frac{11}{64}$ inches. This circumferential spacing of the blades was obtained by removing from the eight bladed ice cutting unit 29, shown in Figure 1, two adjacent blades thereby increasing the spacing between the two blades that bordered the removed blade to $4\frac{11}{64}$ inches. Thus, increasing the spacing between these two cutting blades, increased the width of the ice edge portion removed by the following of these blades so that larger ice pieces were produced.

As many possible embodiments may be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

I claim:

1. The method of producing ice in small pieces which comprises: progressively freezing a mass of water into a thin sheet of ice curved about and traveling about an axis of rotation located parallel to the unfrozen surface of the mass of water; and in a zone located above said mass and in the path of travel of said sheet successively separating relatively narrow elongated sheet portions having substantially parallel sides by making a succession of indentations along similar, spaced lines extending from one side edge of the sheet to the opposite side edge thereof and successively imparting to each sheet portion lying in front of each indentation a linear velocity three to five times as great as the linear velocity of the curved sheet behind such indentation.

2. The method of producing ice in small pieces which comprises: progressively freezing water into a thin sheet of ice curved about and traveling about an axis of rotation; and successively separating relatively narrow elongated sheet portions having substantially parallel sides from such

75

sheet by making a succession of indentations along similar, spaced lines extending from one side edge of the sheet to the opposite side edge thereof and imparting to each sheet portion lying in front of each indentation a linear velocity three to five times as great as the linear velocity of the curved sheet behind such indentation.
